CLAIM

The ornamental design for a combined rack and dispenser for spooled wire, substantially as shown.

DESCRIPTION

FIG. 1 is a reduced perspective view of a combined rack and dispenser for spooled wire showing my new design;

FIG. 2 is a side elevational view;

FIG. 3 is a front elevational view, the rear elevational view being the same;

FIG. 4 is a top plan view; and

FIG. 5 is a bottom plan view.
